UNITED STATES PATENT OFFICE.

LEIGH J. BAIR, OF NEW YORK, N. Y.

TIMER.

Application filed January 15, 1921. Serial No. 437,513.

To all whom it may concern:

Be it known that I, LEIGH J. BAIR, a citizen of the United States, and a resident of the city of New York, borough of Manhattan, county and State of New York, have invented a new and Improved Timer, of which the following is a full, clear, and exact description.

This invention relates to timers for internal combustion engines and particularly to an improved timer for a Ford engine and has for an object to provide a construction which is simple, strong and which will have positive operation continuously.

Another object of the invention is to provide a timer for Ford automobiles in which a sliding contact is arranged between the contact post and the rotor whereby an even wear is produced on all of the parts and whereby there will be no jumping of the contact brush and adjacent the contact section of the rotor.

A further object more specifically is to provide a timer formed of insulating material with a contact breaker of insulating material and formed as a disc with a single metallic section so that a rubbing engagement may be continually provided.

In the accompanying drawings—

Figure 1 is a front elevation of a timer disclosing an embodiment of the invention.

Figure 2 is a sectional view through Figure 1 approximately on line 2—2.

Figure 3 is a fragmentary sectional view through Figure 1 approximately on line 3—3.

Figure 4 is a front elevation of the contact breaker shown in Figure 2.

Figure 5 is a view similar to Figure 4 but disclosing a modified form of contact breaker.

Figure 6 is an edge view of the structure shown in Figure 5.

The timer disclosed in the accompanying drawings is made a proper shape to fit into the place provided for an ordinary timer now in common use on Ford automobiles so that in order to use the timer embodying the invention on a Ford automobile it will be merely necessary to remove the old timer and substitute the new one. As is known, the ordinary timer now in common use on Ford automobiles consists of stationary contacts with a breaker having a rotor adapted to roll over these contacts at the proper time. This action produces undesirable re-

sults by reason of the fact that there are different materials involved and, consequently, an uneven wear on the surface results, said uneven wear producing raised portions at the points of contact which by reason of the high speed of the parts causes the brushes to jump and oftentimes fail to engage the respective contacts. Also, difficulties are caused by the accumulation of oil on the various contacts so that often the desired spark cannot be secured.

In the present invention it is aimed to overcome these difficulties by providing a construction in which a sliding or rubbing contact is provided which in a certain sense acts as an automatic cleaner as well as a make and break mechanism. Also the action of the rotor throws off any oil deposited thereon and, consequently, leaves the contacts free to provide a good connection and, consequently, to permit a good spark at the proper time. The timer requires no oil or other attention for its operation.

Referring to the accompanying drawings by numeral, 1 indicates a casing constructed of insulating material which is held in place by a suitable spring 2 of the usual construction and arrangement, said spring co-acting with the flange 3 so as to hold the casing 1 in proper place and allow the spark advance rod operating in the aperture 4 to properly shift the casing and the contacts carried thereby whenever desired. Co-acting with the casing 1 is a rotor 5 provided with a tubular shank 6 having an aperture 7 arranged therein whereby the retaining pin 8 may extend through the shank 6 and also through the aperture 7 as well as the slot in the timer shaft 9. By reason of this connection the rotor 5 is operated at the proper speed and is held against the respective contact blocks 10. The rotor 5 is made from a disc 11 of metal having a thickened section 12 which acts as the breaker contact while the remaining contact of the disc 11 is covered with an insulating material 13 which may be rubber, bakelite or other material which will stand more or less wear caused by the blocks 10. It will be noted that the blocks 10 continually press against the rotor 5 and as each block 10 engages the metal section 12 it will complete the circuit.

The casing 1 is provided with as many blocks 10 as there are cylinders in the engine which is disclosed as 4. Each of these

blocks may be of any suitable conducting material, as for instance, carbon and is provided with a reduced section 14 having a groove therein for receiving one end of the 5 spring 15. The opposite end of the spring is clamped against the casing 1 by the head 16 of a screw 17. In this way, each of the blocks 10 are resiliently held in their guiding socket 18. The screw 17 is clamped in 10 place by a suitable nut 19 while a contact nut 20 clamps the wire 21 to the screw for completing the circuit at this point. The spring 2 acts to hold the casing and other parts in proper position while the various 15 springs 15 act to take up the wear of the blocks 10 and also the rotor 5 and thereby maintain the parts in proper position for securing a good contact at all times. It will be noted that the blocks 10 slide or rub against 20 the insulation 13 most of the time and, consequently, this insulation must be of sufficiently hard rubber or other material to withstand this rubbing action for an appreciable time. It will, of course, be understood that the insulation 13 may be of 25 any thickness desired.

In Figures 5 and 6 a slight modified form 30 of rotor is shown in which the insulating material 13' is the full thickness of the rotor except at the control segment 12'. The control segment 12' merges into a shank 6 which shank is provided with a plurality of anchors 22 having overhanging shoulders 23 whereby the material 13' may 35 readily interlock therewith. In order to cause the insulating material 13' to properly interlock with the control segment 12', said

thickened section may be provided with grooved edges 24 as shown in Figure 6.

What I claim is:—

1. A timer of the character described comprising a molded casing of insulating material formed with a plurality of integral 40 equally spaced sockets arranged interiorly thereof and extending parallel with the axis 45 of the casing, a contact block arranged in each of said sockets, means for connecting a conducting wire with each of said contact blocks and a disk-shaped contact breaker positioned in the casing so one side thereof 50 will engage all of said blocks, said disk having a face of insulating material except at one point.

2. A timer of the character described comprising a casing constructed of insulat- 55 ing material and provided with a disk-shaped body having an annular flange extending from one face and a spring receiving hollow projection from the other face, said body being also provided with integral 60 socket members extending from the same face as the annular flange, said sockets being grouped in a circle centrally within said flange, a plurality of spring pressed contacts arranged in said sockets, and a 65 contact breaker continually engaging said contacts, said breaker being formed with a narrow conducting section and an insulating section, said sections being all in the same plane, and means for connecting a conduct- 70 ing wire to each of said spring pressed contacts.

LEIGH J. BAIR,
